UNITED STATES PATENT OFFICE.

BERNARD W. CARRINGTON, OF HEPPNER, OREGON.

CONDUCTOR'S RAILWAY-INDICATOR.

SPECIFICATION forming part of Letters Patent No. 499,517, dated June 13, 1893.

Application filed September 5, 1892. Serial No. 445,043. (No model.)

To all whom it may concern:

Be it known that I, BERNARD W. CARRINGTON, a citizen of the United States, residing at Heppner, in the county of Morrow and 5 State of Oregon, have invented a certain new and useful Improvement in Conductors' Railway-Indicators; and I do hereby declare the following to be a full, clear, and exact description of the invention, such as will enable 10 others skilled in the art to which it appertains to make and use the same.

My invention relates to a novel indicator adapted to be carried in the pocket and especially intended for the use of railway conductors to indicate the business or train orders to be executed at the various stations along the line, and has for its object to provide such a device that shall reduce the liability of overlooking any of such duties to a 20 minimum and that shall be capable of repeated or perpetual use and upon an unlimited number of different lines.

To these ends my invention consists in the novel construction and arrangement herein- 25 after fully described and afterward definitely pointed out in the claims following, due reference being had to the accompanying drawings forming a part of this specification, wherein—

30 Figure 1 is a plan view of my improved indicator; Fig. 2 a section on the line $x-x$, and Fig. 3 a section on the line $y-y$, Fig. 1.

In constructing my improved indicator I 35 preferably make it in the form of a book, the letter A indicating the front and A' the back covers thereof. Said covers may be formed of stiff paper board, leather, or other suitable material, and of a size to be conveniently carried in the pocket. Upon the inside of the 40 cover A is formed a pocket for the reception of a tablet B which may be conveniently formed as follows: To the two sides and bottom edges of the cover A is secured by any adhesive material or other suitable means a strip 45 a, and to said strip is likewise secured a rectangular frame a' that slightly overlaps the inner edges of the strip a, thus forming a pocket within which may be slipped the tablet B. Said tablet is provided upon its oppo- 50 site sides with erasive surfaces adapted to have marked thereon by means of a pencil memoranda of the duties to be performed at

the different stations. Upon the inside of the cover A' is disposed a frame C, said frame being provided with a series of parallel and horizontally arranged rectangular slots c and a similar series of shorter slots c' disposed along its inner edge. Between the cover A' and the frame C are secured by an adhesive substance or other suitable means strips d, d', 55 d² and d³, the strips d, d', being secured between said frame and the cover at the sides, the strip d² at the bottom and the strip d³ at a point between the slots c and c', forming a series of pockets beneath said slots. Within 60 the pocket formed beneath the slots c' is slipped a narrow tablet E, its opposite sides being provided with erasive surfaces adapted to have marked thereon the names of the stations along the line which are visible through 65 the slots c'. Within the pockets formed beneath the slots c are arranged slides F provided with projecting tabs f. Said slides are about one half the length of the slots c. To the 70 inside of the cover A' beneath said slots are 75 secured colored strips G of substantially the same length as the slides F and arranged adjacent to and opposite the slots c'. When the slides F are pushed toward the center of the covers by means of tabs f said colored strips 80 will be covered by said slides and hid from view, and when said slides are moved in the opposite direction the colored strips opposite the names of the stations upon the tablet E 85 will be exposed.

The operation of my improved indicator is as follows:—Before starting out upon the route the conductor marks upon the tablet E the names of the stations along the line in their respective order and slips the same within its 90 pocket upon the cover A'. He also makes memoranda upon the tablet B of services to be performed at the different stations in such manner that said memoranda will appear upon the tablet B opposite the names of the 95 stations upon the tablet E at which the services are to be performed. The slides F opposite those stations are then withdrawn to one side so as to disclose the colored strips G, which serve to direct the conductor's attention to the stations at which he is to perform certain services, the nature of the services being indicated by the memorandum written upon the tablet B opposite the name of the 100

station. For the sake of illustration let it be supposed that the train has arrived at the station named Laurel. Upon referring to his indicator the conductor sees the color strip 5 opposite the name of this station uncovered, which indicates to him that he has some duty to be performed at this place. Upon inspecting the tablet B he finds indicated thereon opposite the name of the station the nature 10 of such duties, such as switching one or more cars off on to a siding or picking up a car lying at said station, or such other services as he has previously received orders to perform.

The tablets B and E being provided with 15 erasive surfaces can be used repeatedly and by furnishing both sides of said tablets with such surfaces the names of the stations and the memoranda of the duties to be performed can be marked upon both sides, so that by 20 reversing the tablets a large number of stations and such memoranda can be indicated thereon, thus greatly economizing space.

Instead of applying colored strips to the cover A', as described, the cover itself may 25 be colored at the proper points, and I prefer to employ a vivid color, such as red for example, that will instantly attract attention and reduce the liability of the station being passed unnoticed.

30 I have described the device as being made in book form, but it may also be made in one rigid piece if desired.

I would have it understood that I do not 35 limit myself to the precise arrangement of slides and colors opposite the name of each station as shown by the drawings. This construction may be modified by providing two colors and slides for covering said colors op-

posite the name of each station, so that either of said slides may be slid to expose either of 40 said colors to indicate certain duties to be performed at this station.

Having described my invention, what I claim is—

1. An indicator having the back A, A', the 45 back A being provided with a pocket carrying a removable and reversible erasive tablet B, and the back A' being provided with a pocket carrying a removable and reversible erasive tablet E and provided with a series of parallel and horizontally arranged pockets, of slides 50 F fitted to slide in said pockets and adapted to cover and uncover indicating colors or symbols disposed within said pockets adjacent to the tablet E, substantially as shown and described and for the purpose specified.

2. An indicator having folding backs A, A', the strip a secured to the side and bottom edges of the back A, the frame a' secured to said strip, the tablet B supported between 60 said back and frame, the frame C disposed upon the back A', and provided with two series of horizontal and parallel slots c, c', the strips d, d', d², d³, secured to and between said frame and back A in the manner shown, 65 and slides F fitted in the slots c between said frame and back and adapted to cover and uncover indicating colors or symbols as shown and described and for the purpose specified.

In testimony whereof I affix my signature in 70 presence of two witnesses.

BERNARD W. CARRINGTON.
